UNITED STATES PATENT OFFICE.

JOHN WILLIAM BRADLEY, OF LEEDS, ENGLAND.

EXPANDING BORING-HEAD AND SCREWING-HEAD.

1,176,812.

Specification of Letters Patent. Patented Mar. 28, 1916.

Application filed April 11, 1913. Serial No. 760,532.

To all whom it may concern:

Be it known that I, JOHN WILLIAM BRADLEY, a subject of the King of Great Britain and Ireland, residing at Leeds, in the county 5 of York, England, have invented new and useful Improvements in Expanding Boring-Heads and Screwing-Heads, of which the following is a specification.

This invention relates to an expanding 10 and collapsing boring head and internal screwing head, the object of my present improvement being to provide for a minute adjustment of the cutters or dies and to insure an accurate working of the same with a 15 minimum of wear.

My present invention consists essentially in the application of a floating or rotating cam center to each sliding jaw, in conjunction with a micrometer adjustment device 20 applied to the locking plunger.

Description of drawings.—Figure 1 is an end elevation of an expanding and collapsing boring and screwing head having my present improvements applied. Fig. 2 25 is a sectional side elevation of Fig. 1. Fig. 3 is an end elevation, Fig. 4 a side elevation, and Fig. 5 a plan, of sliding jaw fitted with the floating cam center. Fig. 6 is an end elevation, and Fig. 7 a side elevation, of 30 sliding jaw fitted with a slightly modified form of floating cam center. Fig. 8 is an end elevation, and Fig. 9 is a sectional side elevation of recessed annular cam plate for same. Fig. 10 is an end elevation. Fig. 11 35 is a side elevation, and Fig. 12 a plan, of sliding jaw fitted with a further modified form of floating cam center. Fig. 13 is an end elevation, and Fig. 14 a sectional side elevation, of recessed annular cam plate for same.

40 The same letters of reference are employed throughout the specification and drawings to indicate corresponding parts.

According to my invention, tools or dies A are carried in jaws B which are slidably 45 fitted in corresponding external recesses or pockets within the main body C of the head. A series of sliding jaws B are adjustable radially within the recesses or pockets by means of an intermediate cam plate F having a series of cam rises or recesses G which are adapted to engage with recesses or protrusions in or from the sliding jaws B. The said cam plate F is held up to the sliding jaws B by means of an outer disk or plate H 50 fitting on a projecting boss from the main body, this outer disk or plate H being locked against a shoulder by means of an annular

check nut or the like. This outer disk or plate H has an internal circumferential recess extending a considerable distance 60 around that face abutting the plate F within which recess is fitted a cylindrical tension spring, one end of which is secured to the cam plate F and the other to the disk H.

It may be mentioned that the disk H is 65 locked in position on the cutter head while the cam plate F is normally free to revolve. The outer disk or plate H is provided also with a circumferential slot O of suitable length having a recess on its inner face and 70 within this slot O is fitted a sliding block Q having a corresponding inner shoulder 75 adapted to engage with the said recess. This is particularly illustrated in Fig. 2. This sliding block Q carries a cylindrical plunger box S within which is fitted a spring plunger pin T adapted to engage with a hole U in the face of the intermediate cam plate F. The outer end of the plunger box S is fitted with a nut V for locking the sliding block Q 80 and its plunger box S within the circumferential slot O.

One of the principal features of my present invention is a micrometer adjustment to be applied to this spring pressed 85 plunger device which slides in the circumferential slot O of the outer disk or plate H. The cylindrical plunger box S is carried in an elongated or slotted bearing g formed in a rotatable ring h which is recessed into the 90 face of the outer disk or plate H, and is secured therein by means of T bolts i working within a T-shaped circumferential recess j. The rotatable ring h has a pair of 95 projecting lugs k and l, one on each side of the plunger device, one lug k carrying a micrometer screw m of any suitable type (graduated preferably in thousandths of an inch or according to the metric scale) and the other lug l carrying a suitable locking screw 100 n the micrometer screw m and the locking screw n abutting on opposite sides against a collar O interposed between the plunger locking nut V and the outer disk or plate H.

In adjusting the cutters or dies A, the T 105 bolts i and the plunger locking nut V are slackened and the ring h carrying the plunger device is rotated to obtain first an approximate adjustment of the plunger device, the sliding block Q being held up to 110 the faces of its slot O during this movement by means of an auxiliary spring p. The T bolts i are then tightened, locking the ring h securely in position. The final adjustment

of the plunger device is then obtained by sliding the plunger device along its slotted bearing *g* in the ring *h* by means of the micrometer screw *m*, in which adjusted position it is locked by means of the plunger locking nut *V* and the locking screw *n*. The annular cam plate *F* is then rotated in the usual manner for engagement of its register hole *U* with the plunger pin *T* to determine the cutting position.

The recess *a* in which each projecting cam *G* engages to radially adjust its respective sliding jaw *B* within its external pocket, is formed (see Figs. 1 to 5) in a floating or rotating cam center *b* mounted in the sliding jaw *B*, this arrangement being designed so that the recess *a* will conform to the cam rises *G* in any position of the annular cam plate *F*, thus overcoming the difficulty due to the center of rotation of the cam plate *F* not coinciding with the centers of curvature of the cam rises *G*. The necessity for play or looseness in the recess *a* (in a radial direction) is thus obviated, so that the recess *a* can be made a perfect sliding fit upon the cam rise and the recess, thus insuring absolute and permanent accuracy in the radial adjustment of the series of sliding jaws *B* carrying the cutters or dies *A* with a minimum of wear.

In some cases the floating or rotating cam center *b*, instead of having the recess *a* engaging the projecting cam rise *G*, is formed with like effect (see Figs. 6 to 9) with a projection *c* integral therewith and engaging within a correspondingly recessed cam path *d* in the annular cam plate *F*. Or the floating or rotating cam center *b* may have a larger projection *e* (see Figs. 10 to 14) mounted loosely thereon and in engagement with a correspondingly recessed cam path *f* in the annular cam plate *F*.

In adjusting the cutters or dies *A*, the plunger pin *T* is withdrawn clear of the cam plate *F*, the *T* bolts *i* and the plunger locking nut *V* are slackened, and the ring *h* carrying the plunger device and index finger is rotated to obtain first an approximate adjustment of the plunger device by means of the graduated scale on the outer disk or plate *H*, the sliding block *Q* being held up to the face of its slot *O*, during this movement (to facilitate easy sliding) by means of an auxiliary spring *p*. The *T* bolts *i* are then tightened, locking the ring *h* securely in position. If after trial a further fine adjustment of one or more thousandths of an inch (plus or minus) is required, this final and known adjustment of the plunger device is then obtained by easing the screw *n* and sliding the plunger device in the direction desired along its slotted bearing *g* in the rotatable ring *h* (now locked) by means

of the micrometer screw *m* with its known graduations, in which adjusted position it is locked by means of the plunger locking nut *V* and the locking screw *n*. The annular cam plate *F* is then rotated in the usual manner for engagement of its register hole *U* with the plunger pin *T* to determine the cutting position.

I claim:

1. In an expanding and collapsing boring and internal screwing head, in combination, a rotatable annular cam plate having projecting cam rises thereon, radially slideable jaws, female cam shoes pivotally secured to said jaws and adapted to engage with said projecting cams, a plunger co-acting with the annular cam plate, means for obtaining the primary approximate adjustment of the plunger and micrometer means for obtaining the final adjustment of the plunger.

2. In an expanding and collapsing boring and internal screw threading head, in combination, a rotatable annular cam plate having recessed cam grooves therein, radially slideable jaws adapted to have cutting tools secured therein, shoes pivotally secured to said jaws having heads formed integral and adapted to slidably engage in said cam recesses, a plunger co-acting with the annular cam plate, means for normally pressing the plunger into engagement with the cam plate, a locking screw adapted to engage the plunger and a micrometer adjusting means diametrically opposite the locking screw designed to engage the plunger.

3. In an expanding and collapsing boring and internal screw threading head, in combination, a rotatable cam plate, having an orifice therein, radially slideable tool holding jaws adapted to be engaged by said cam plate, spring means for rotating said cam plate, a head having a concentric slot and an annular recess in the rear thereof, a spring plunger adjustably secured in said slot and having a pin adapted to engage the orifice in said cam plate, a ring having an opening adapted to provide clearance for said spring plunger and to be clamped in any desired position in said annular recess, brackets secured on diametrically opposite sides of the opening in said ring, a micrometer adjustment device secured to one of said brackets adapted to regulate the movement of said plunger box, a pointer on said plunger box adapted to co-operate with a graduated scale on the rear of said head and with said micrometer device, and a locking screw making threaded engagement with the other bracket, substantially as described.

JOHN WILLIAM BRADLEY.
